Primary Examiner — Kevin K Rudzinski(74) *Attorney, Agent, or Firm* — Tarolli, Sundheim, Covell & Tummino LLP(57) **CLAIM**

I claim the ornamental design for a temperature regulation garment, as shown and described.

DESCRIPTION

FIG. 1 is a front view of a first embodiment of a temperature regulation garment comprising a new, original and ornamental design;

FIG. 2 is a rear view of the temperature regulation garment shown in FIG. 1;

FIG. 3 is a front view of a second embodiment of a temperature regulation garment; and,

FIG. 4 is a rear view of the temperature regulation garment shown in FIG. 3.

The broken lines in the drawings depict unclaimed environmental subject matter.

The pockets shown in the Figures are of a patch type with no significant thickness into and out of the plane of the page.
